DOOR CHIME SIGNAL HOUSING

John G. Jolly, Cincinnati, Ohio, assignor to Nutone, Inc.,
Cincinnati, Ohio, a corporation of New York

Application March 10, 1958, Serial No. 49,981

Term of patent 14 years

(Cl. D72—1)

Figure 1 is a front elevational view of a door chime signal housing incorporating my new design.

Figure 2 is a side elevational view thereof.

Figure 3 is a top plan view.

Figure 4 is a cross sectional view taken on the line 4—4 of Figure 1.

The side and bottom not shown are, respectively, identical to the side shown in Figure 2 and the top shown in Figure 3.

I claim:

The ornamental design for a door chime signal housing, substantially as shown and described.
